WHEELED TOY

Harold B. Morris, Akron, Ohio

Application December 16, 1946, Serial No. 716,568

3 Claims. (Cl. 46—111)

1

My invention relates to improvements in wheeled toys.

This application is a continuation in part of divisible subject matter from that now claimed therein of my allowed application for patent for Wheeled sounding toy, S. N. 306,513, filed February 28, 1939, now Patent No. 2,428,124.

An object of my invention is to provide a structure which will provide a plurality of air impulses on each revolution of a set of wheels of the wheeled toy. These pluralities of impulses may be employed to successively actuate separate sound devices or successively inflate pneumatic toy portions or to alternately actuate a sound device and actuate an inflatable portion during said revolution of said set of wheels, or if desired said wheeled toy may be constructed to function so that said plurality of impulses may occur simultaneously at a point in said revolution. Where a plurality of sound devices are actuated during each revolution of the wheel, it is obvious that my improved structure may make a succession of sounds produced so rapidly as to substantially produce a blended chord, or if desired more slowly to produce the successive notes of a scale or tune. Where pneumatic portions of a toy are successively deflated and inflated by each impulse, it is apparent that I am enabled to provide a pneumatic toy employing one or more figures having inflatable portions successively rapidly actuated to simulate intense animation or action.

A further object of my invention is to provide a toy of the above desirable characteristics constructed of a few, simple but strong and easily replaceable parts.

These and such other objects of my invention as may hereinafter appear will be best understood from a description of the accompanying drawings which illustrate various embodiments thereof.

In the drawings,

Fig. 1 is a side elevation of one embodiment of a wheeled toy constructed in accordance with my invention comprising a sounding toy having air pump means and sounding means.

Fig. 2 is a vertical sectional view taken along the line 2—2 of Fig. 1.

Fig. 3 is a side elevation of another embodiment of my invention comprising a wheeled animated toy having two boxers mounted thereon, one with portions inflated and the other with complementary portions deflated.

Fig. 4 is a side elevation of the embodiment of my invention shown in Fig. 3 showing the two

2

boxers having their opposite complementary portions respectively deflated and inflated.

Fig. 5 is a side elevation of a further embodiment of my invention comprising a combination sound and animated wheeled toy having two people in the act of embracing with the successive air pulsations thereof causing such embracing motion and a sound between each embrace during each revolution of said set of wheels.

Fig. 6 is a sectional view taken along the line 6—6 of Fig. 5.

In the drawings, wherein like characters of reference generally indicate like parts throughout, 10 generally indicates a wheeled toy constructed in accordance with my invention.

Such a wheeled toy usually includes a frame 12 of substantially the length of the toy and usually provided with a floor 14 for mounting of the toy elements thereon and provided with 20 suitable means for mounting the axles thereon, namely, the front axle 17 having the wheels 19 on the ends thereof and the rear axle 20 having the wheels 22 on the ends thereof. One of said axles 17 or 20, in the embodiment shown the rear axle 20, is rotatable on movement of the set of wheels 22 and is provided with eccentric crank means 24, in the embodiment shown comprising an eccentric crank portion 24 rotatable simultaneously with the wheels with the same R. P. M's.

30 In the embodiment shown, the eccentric crank portion 24 is preferably provided with the roller 26 thereon. The plurality of air impulses on each revolution of the set of wheels 22 are provided by said eccentric crank portion 24, or crank means successively contacting a plurality of air sacks on each revolution thereof in synchronism with each revolution of the set of wheels. For this purpose I arrange a succession of a plurality of deflatable, self-inflatable air sacks, in

40 the embodiments shown the two air sacks 28^a and 28^b in succession on the inner periphery of the cylindrical wall 38 of a casing 40 mounted over said rear axle 22 to surround the orbit of said eccentric crank portion, said wall 38 being located concentrically of said axle and at a slightly circumferentially spaced distance from said orbit, said air sacks 28^a and 28^b being of such a size that they are successively deflated by said eccentric crank portion 24 as it travels on its orbit. Said air sacks 28^a and 28^b are preferably constructed of a suitable elastic and resilient material, preferably rubber, that is capable of returning to a self-inflatable position after compression or deflating. Said eccentric crank portion 24 thus successively contacts said air sacks

50 55

28^a and **28^b** to successively deflate them against the inner periphery of said cylindrical wall **38** on each revolution of said eccentric crank portion **24**. The sacks **28^a** and **28^b** are in the nature of an atomizer bulb and may, if desired, be similarly provided with a one-way valve as is often employed in such atomizer bulbs to permit the intake of air for self-inflation thereof.

In all embodiments shown said cylinder is provided with suitable orifices **42^a** and **42^b** on the periphery thereof to receive the open neck portions **30^a** and **30^b** of said air sacks, in the embodiment shown being located at diametric portions of said cylinder wall **38**.

In the embodiment of my invention shown in Figs. 1 and 2, I have shown my invention as applied to a wheeled sounding toy **10**, whereas in the embodiment of my invention shown in Figs. 3 and 4, I have shown my invention as applied to a wheeled animated toy **10'** and in the embodiments shown in Figs. 5 and 6 I have shown my invention as applied to a combination wheeled sounding and animated toy **10''**.

Insofar as the principles of my invention are concerned, it is obvious that any type of locomotion may be employed for the wheeled toy, namely, that it may be operated by electrical power, mechanical power, or by human or animal power itself.

My invention may be adapted to simulate sounds which have particular appeal to children and for this purpose I employ said succession of air impulses to actuate the sounding means **16^a** and **16^b** as shown in Figs. 1 and 2 preferably composed of a plurality of reeds each preferably of different vibratory characteristics capable of producing different sounds. The type of reeds used are preferably such as shown in my copending application S. N. 306,513, now Patent No. 2,428,124, although if desired, other types of sounding devices may be employed. As stated hitherto, the respective reeds are adapted to oscillate in use.

In order to reflect and concentrate the sound produced by the individual reed means, I preferably employ in combination therewith, horn means **18** for said reeds, in my preferred embodiment comprising an individual horn **18^a** and **18^b** for each respective reed **16^a** and **16^b**. The respective reeds **16^a** and **16^b** are mounted in the respective horns and in the embodiment shown the ends **44^a** and **44^b** of the open neck portions **30^a** and **30^b** preferably have a bead **46^a** or **46^b** to enclose the smaller ends of said respective horns **18^a** and **18^b**. It is obvious that any type of reed structure known in the art may be employed, preferably one as shown of a size less than the area of the horn mouth piece so as to permit an influx of air through said mouth piece from the outer end of the horn for a purpose to be described, and yet capable of vibration on the efflux of air out through said horn to provide the desired sound. It is thus apparent that for this purpose the areas of the reed structures **16^a** and **16^b** are less respectively than the areas of the respective mouth pieces **36^a** and **36^b** of said horns. While I preferably employ the deflatable air sacks **28^a** and **28^b**, it is obvious that any of the equivalent types of air pumps may be employed, such as a standard type of bellows, pistons, diaphragms, etc. I have found that for purposes of cheapness, any suitable type of rubber air sack may be employed, preferably one which is inherently self-inflatable, namely, one in which the rubber tends to resiliently resume its original shape, the air for this purpose of self-inflation in my preferred

embodiment passing around the portions of the horn mouth pieces **36^a** and **36^b** not taken up by the respective reed structures **16^a** and **16^b**.

It is thus obvious that on rotation of the axle **20**, the roller **26** will successively pass over the surfaces of the air sacks and compress them against the inner periphery of said cylinder **40** to deflate them so that the air being forced out will actuate the sounding means. When the roller **26** has passed over the surface of the air sacks they will resiliently inflate themselves to their original position drawing air back through the sounding means and necks so as to be ready for later deflation.

In the embodiment of my invention shown in Figs. 3 and 4 I have shown figures simulative of two boxers. Each boxer **48** or **50** has a portion **52** or **54** respectively capable of being inflated or deflated upon actuation of the toy. Although I have shown arm portions **52** and **54** of each figure **48** and **50** capable of being actuated, it is understood that the whole object may be constructed to be animated. Said arm portions may be constructed of a rubber or any suitable material that can be formed into a part designed to hang loosely until inflated, but not of resilient self-inflatable material like the air sacks **28^a** and **28^b**. Upon inflation the portion may come to any position that it be designed to attain. I have provided said air pump means comprising the air sacks **28^a** and **28^b** and eccentric crank portion **24** adapted to alternately inflate the portions desired to be animated in the opposing figures shown. In place of the sounding means **16^a** and **16^b** I have extended the necks **30^{a'}** and **30^{b'}** of the air sacks **28^{a'}** and **28^{b'}** so that the air expelled therefrom may be guided to a portion such as the arm portion **52** of the boxer **48** and to the arm **54** of the boxer **50**. As shown in Fig. 3, the eccentric crank portion **24** has compressed the sack **28^{a'}** forcing the air through the elongated neck **30^{a'}** and into the inflatable arm portion **54** of the boxer **50** causing the arm to be inflated thereby moving and causing animation, self-inflation of the air sack **28^{b'}** causing deflation of the arm portion **52** of the boxer **48**, causing it to lie limp at his side as shown.

As the eccentric crank portion **24** passes on to the sack **28^{b'}** the sack **28^{a'}** returns to its normal shape drawing the air out of the arm portion **54** causing it to shrink and drop to the position shown in Fig. 4. At this instant the eccentric crank portion **24** then compresses the sack **28^{b'}** causing the air to inflate the arm portion **52** of the boxer **48** causing it to move from a deflated position to a position contacting the boxer **50** as shown in Fig. 4. The toy is thus so constructed so as to cause said arm portions of the boxers to alternately be actuated, thereby simulating a boxing match with first one boxer striking the other and vice versa. It is thus obvious as long as the wheeled toy is kept in motion this action will continue and the faster the motion the faster the action.

As shown in Figs. 5 and 6 in place of sounding means **16^a** I have provided the neck **30^{a''}** of the air sack **28^{a''}** with branches **58** and **60** to simultaneously inflate the inflatable and deflatable arm portions **62** and **64** of the two lovers **66** and **68**. As the eccentric crank portion **24** deflates the sack **28^{a''}** the arms **62** and **64** are raised from the dotted line positions to the full line positions causing the lovers to embrace. It is apparent that upon further rotation of the eccentric crank portion **24** from the sack **28^{a''}**,

the sack 28^a'' will self-inflate causing the arms 62 and 64 to deflate and drop to the dotted line positions shown in Figs. 5 and 6. The simultaneous compression of the sack 28^b'' will cause the air to pass through the sounding means 16^b'' to emit a sigh or a groan or whatever sound is desired, between each embrace on each revolution of the wheels 22.

It is apparent that any other characters or objects capable of being inflated and deflated may be employed.

It is apparent, therefore, that I have provided a novel type of wheeled sounding and/or animated toy with the advantages described above.

It is understood that my invention is not limited to the embodiments shown and that various deviations may be made therefrom without departing from the spirit and scope of the appended claims.

What I claim is:

1. In a wheeled sounding toy, ground engaging wheels, a frame, an axle mounting said wheels having eccentric crank means rotatable on revolution of at least one of said wheels, a hollow cylinder of greater radius than said eccentric crank means mounted on said frame to surround the orbit of said eccentric crank means, a plurality of sounding reeds, a horn enclosing each reed and a plurality of deflatable self-inflatable air sacks having necks and bodies with the necks of said air sacks extending exterior of said cylinder and each neck having a reel mounted in the open end thereof and the bodies of said sacks arranged in succession on the inner periphery of said cylinder so that in inflated condition they extend into the orbit and path of said eccentric crank means, whereby said air sacks but not said necks are deflated by said eccentric crank means the air being forced therefrom through the necks to actuate said reeds on each revolution of said wheel.

2. In a wheeled sounding toy, ground engaging wheels, a frame, an axle mounting said wheels having eccentric crank means rotatable on revolution of at least one of said wheels, a hol-

low cylinder of greater radius than said eccentric crank means mounted on said frame to surround the orbit of said eccentric crank means, a plurality of air actuated sound devices and a plurality of deflatable self-inflatable air sacks having necks and bodies with the necks of said air sacks extending exterior of said cylinder and each neck having a sound device connected to the open end thereof and the bodies of said sacks arranged in succession on the inner periphery of said cylinder so that in inflated condition they extend into the orbit and path of said eccentric crank means, whereby said air sacks but not said necks are deflated by said eccentric crank means the air being forced therefrom through the necks to actuate said sound devices on each revolution of said wheel.

3. In a wheeled toy, ground engaging wheels, a frame, an axle mounting said wheels having eccentric crank means rotatable on revolution of at least one of said wheels, a hollow cylinder of greater radius than said eccentric crank means mounted on said frame to surround the orbit of said eccentric crank means, toy devices having at least portions thereof pneumatically operated mounted on said frame and a plurality of deflatable self-inflatable air sacks having necks and bodies with the necks of said air sacks extending exterior of said cylinder and each neck having the open end thereof connected to a pneumatically operated toy portion and the bodies of said sacks arranged in succession on the inner periphery of said cylinder so that in inflated condition they extend into the orbit and path of said eccentric crank means, whereby said air sacks but not said necks are deflated by said eccentric crank means the air being forced therefrom through the necks to actuate said pneumatically operated toy portions on each revolution of said wheel.

HAROLD B. MORRIS.
